UNITED STATES PATENT OFFICE.

LEWIS A. HIGHHOUSE, OF HONESDALE, PENNSYLVANIA.

WIRE-STRETCHER.

1,216,809.

Specification of Letters Patent. Patented Feb. 20, 1917.

Application filed November 11, 1916. Serial No. 130,853.

To all whom it may concern:

Be it known that I, LEWIS A. HIGHHOUSE, a citizen of the United States, residing at Honesdale, in the county of Wayne and 5 State of Pennsylvania, have invented certain new and useful Improvements in Wire-Stretchers, of which the following is a specification, reference being had to the accompanying drawings.

- 10 This invention relates to certain improvements in wire stretchers and has relation more particularly to a device of this general character of a jointed lever grip type; and it is an object of the invention to provide 15 a device of this general character having novel and improved means whereby an effective grip is had with the wire to be stretched and whereby efficient coaction is had with a post or other fulcrum member. 20 The invention consists in the details of construction and in the combination and arrangement of the several parts of my improved stretcher whereby certain important advantages are attained and the device is 25 rendered simpler, less expensive and otherwise more convenient and advantageous for use, all as will be hereinafter more fully set forth.

The novel features of the invention will 30 hereinafter be definitely claimed.

In order that my invention may be the better understood, I will now proceed to describe the same with reference to the accompanying drawings, wherein—

35 Figure 1 is a view in top plan illustrating a wire stretcher constructed in accordance with an embodiment of my invention and in applied position, said device being shown at a point intermediate its pulling operation;

40 Fig. 2 is an enlarged view in top plan of the device as herein embodied with one of the members shown in open adjustment;

Fig. 3 is a view in edge elevation of the device as herein disclosed; and

45 Fig. 4 is a sectional view taken substantially on the line 4—4 of Fig. 3, and looking in the direction of the arrow.

As disclosed in the accompanying drawings, A and B denote coacting sections comprised in my improved wire stretcher and as herein embodied, the section A includes a head 1 preferably of metal and rectangular in cross section and which is provided with a shank 2 suitably secured, as at 3, to the 50 elongated handle member 4 preferably of wood.

The outer end of the head 1 is provided at substantially its center with the outwardly directed extension 5, the side faces of which being flat and the shoulders 6 at opposite sides of the extension 5 are obliquely disposed on a predetermined angle and the outer margins of said shoulders 6 are defined by the forwardly directed lips or flanges 7.

The member B is preferably formed of a single length of strap metal bent back upon itself to afford the parallel arms 8 disposed at opposite sides of the extension 5 and pivotally engaged therewith as indicated at 9. The inner ends 10 of the arms 8 are disposed on an incline corresponding to the incline of the shoulders 6 so that the movement of the member B in one direction about the pivot 9 is limited.

The wire W to be stretched is adapted to be clamped between a shoulder 6 and an end 10 of an arm 8 and in order to reduce to a minimum the possibility of the wire slipping from therebetween, I find it of advantage to have said ends 10 serrated, as indicated at 11, in Fig. 4 of the accompanying drawings.

The member B is of such a length as to extend a predetermined distance beyond the outer end of the extension 5, and the portions of the arms 8 in advance of the extension 5 are offset outwardly, as indicated at 12, so that lateral movement of the stretcher is prevented during the pulling operation and when the outer portion of said member B is in contact with a post P or other support, 90 it coacts as a fulcrum.

The outer marginal portions of the arms 8 or more particularly the portions 12 thereof adjacent the eye points of the shoulders 6 are cut out, as indicated at 14, to afford 95 substantially rounded surfaces for contact with the post P or other member.

By this arrangement it will be perceived that when the handle 4 is pulled the members A and B will have such relative movement as to positively assure a grip upon the wire being pulled.

Initially the outer part of the curved surfaces 14 is caused to contact with the post P or the like so that upon pulling on the handle 4 a greater leverage will be effected, but it will be perceived that as the handle 4 is pulled the member B will slide inwardly of the post P so that the wire W will be brought in close proximity to the post so 110 that the wire may be stapled or otherwise secured thereto. It has been fully demon-

strated in practice that by permitting this sliding movement of the member B upon the post P during the stretching operation, the wire can be much easier held during the 5 stapling operation.

It is also to be noted that the flanges 7 hereinbefore referred to serve to effectively prevent the wire W being drawn sidewise from between the inner ends 10 of the member B and the coacting shoulders 6 and which arrangement in practice is of material import.

From the foregoing description, it is thought to be obvious that a stretcher constructed in accordance with my invention is of an extremely simple and comparatively inexpensive nature and is particularly well adapted for use by reason of the convenience and facility with which it may be assembled, 20 and it will also be obvious that my invention is susceptible of some change and modification without material departure from the principles and spirit thereof and for this reason I do not wish to be understood as 25 limiting myself to the precise arrangement and formation of the several parts herein shown in carrying out my invention in practice, except as hereinafter claimed.

I claim:

- 30 1. A wire stretcher comprising an elongated member provided at one end with a longitudinally disposed extension affording shoulders at opposite sides of said extension, a second member substantially U-shaped in form and disposed at opposite sides of the extension and pivotally engaged therewith, the free ends of said second member coacting with the shoulders of the first member to afford clamping means, the portion of the second member in advance of the extension having its opposite sides offset outwardly, corresponding edges of the offset portions of the second member being disposed on a predetermined inwardly directed curvature.
- 35 2. A wire stretcher comprising an elongated member provided at one end with a longitudinally disposed extension affording

shoulders at opposite sides of said extension, a second member substantially U-shaped in 50 form and disposed at opposite sides of the extension and pivotally engaged therewith, the free ends of said second member coacting with the shoulders of the first member to afford clamping means, the portion of the 55 second member in advance of the extension having its opposite sides offset outwardly, the free ends of the second member and the shoulders of the first named member being disposed on predetermined corresponding inclines, the outer margins of said shoulders 60 being defined by forwardly directed flanges.

3. A wire stretcher comprising an elongated member provided at one end with a longitudinally disposed extension affording 65 shoulders at opposite sides of said extension, a second member comprising an elongated strip of flat material substantially U-shaped in form and disposed at opposite sides of the extension and pivotally engaged therewith, the free ends of said second member 70 coacting with the shoulders of the first named member to afford clamping means, the free ends of the second member and the shoulders of the first member being disposed 75 on predetermined corresponding inclines whereby the movement of the second member about its pivot in one direction is limited, the portion of the second member in advance of the extension having its opposite sides offset outwardly, the edges of the offset portions of the second member adjacent the eye points of the shoulders of the first named member being disposed on a predetermined inwardly directed curvature, the 80 outer margins of the shoulders of the first named member being defined by forwardly directed flanges positioned beyond the outer faces of the adjacent portions of the sides of the second named member.

In testimony whereof I hereunto affix my signature in the presence of two witnesses.

LEWIS A. HIGHHOUSE.
